REFLECTOR FOR FLUORESCENT LIGHTING FIXTURES

Max M. Thomsen, Moundsville, and Richard G. Slauer,
Wheeling, W. Va., assignors to Sylvania Electric Products Inc., a corporation of Delaware

Continuation of applications Ser. Nos. 64,857 and 64,858,
Apr. 24, 1961, and Ser. Nos. 65,416 and 65,425, June 1,
1961. This application Oct. 31, 1961, Ser. No. 67,403

Term of patent 14 years

(Cl. D48—23)

FIGURE 1 is a top perspective view of a reflector for fluorescent lighting fixtures, showing our new design; and

FIGURE 2 is an end elevational view thereof as shown in FIG. 1.

FIGURE 3 is a top perspective view of a modified form of the reflector shown in FIG. 1, and

FIGURE 4 is an end elevational view thereof as shown in FIG. 3.

FIGURE 5 is a top perspective view of a modified form of the reflector shown in FIG. 1; and

FIGURE 6 is an end elevational view thereof as shown in FIG. 5

FIGURE 7 is a top perspective view of a modified form of the reflector shown in FIG. 1; and

FIGURE 8 is an end elevational view thereof as shown in FIG. 7

This is a continuation of our copending applications Serial Nos. D. 64,857 and D. 64,858 both filed April 24,

1961, and Serial Nos. D. 65,416 and D. 65,425 both filed June 1, 1961 all now abandoned.

We claim:

The ornamental design for a reflector for fluorescent lighting fixtures as shown, and described.
